BALLAST STRUCTURE FOR CARGO SHIPS

Peter Thompson, New Orleans, La.

Application October 2, 1945, Serial No. 619,796

25 Claims. (Cl. 114—125)

1

This invention relates to merchant ships and particularly to novel and improved ship hold and collapsible water ballast structures.

One object of the invention is a novel and improved movable ballast structure of the above indicated character which is characterized by the marked ease and facility with which it may be collapsed and stored in compact units within the hold when not needed for water ballast, and, when needed for ballast, may be with equal ease and facility moved and set up in water ballast functioning position to divide the hold into port and starboard sections of multiple ballast compartments.

A further object of the invention is a structure of the above indicated character which is further characterized by its simplicity in construction and manipulation and by the ease of manufacture, assembly and mounting.

Other objects of the invention will hereinafter appear.

For a better understanding of the invention reference may be had to the accompanying drawings forming a part of this application wherein—

Fig. 1 is a diagrammatic plan view of a ship hold embodying my invention;

Fig. 2 is an elevational view of a part thereof;

Fig. 2A is a plan view thereof;

Fig. 2B is a sectional view along the line 2—B of Fig. 2;

Figs. 3 and 4 are elevational views of certain of the ballast elements;

Fig. 5 is a view of the mounting of certain of the elements;

Fig. 5A is an enlarged view of a part of Fig. 5;

Fig. 6 is a diagrammatic plan view of a modification;

Fig. 7 is an elevational view of a part thereof; and

Fig. 8 is a sectional view along the line 8—8 of Fig. 7.

Referring to Figs. 1 to 4, I have illustrated my invention as embodied in the hold of a ship where the side frames MP and MS are substantially straight in the fore and aft direction or have only slight curvatures in that direction as, for example, the midship hold of conventional merchant ships but it is understood that the invention is applicable to other shipholds. The hold is formed by the side frames MS and MP and by the athwart bulkheads N and O. The diagonal lines P and R indicate approximately the area of the ceiling in the way of the hatch which is disposed at the bottom of the hold.

The hold is divided into twelve water ballast

2

compartments 10S, 10P, 11S, 11P, 12S, 12P, 13S, 13P, 14S, 14P, 15S and 15P. The compartments 12S, 12P, 13S and 13P are substantially longer than the other compartments, approaching in length the width of the ceiling. The ballast compartments are formed by five assembly units of collapsible ballast plates, each assembly unit being permanently attached to the hold structure and comprising elements which are storable against the hold frame structure as described below. These assembly units are indicated at 16, 17, 18, 19 and 20.

The assembly unit 20 is disposed along the center line of the ship and comprises center line bulkheads 20A and 20B disposed on the opposite sides of the hatch and connected respectively with the athwart bulkheads O and N. The partitions or bulkheads 20A and 20B are fixed in position and the assembly unit 20 includes a pair of movably mounted ballast plates 1 and 1A, these being hinged to the hatch stanchions or I-beams 21 and 22 at 23 and 24, respectively. The assembly unit 20 thus divides the hold into port and starboard sections, each containing six ballast compartments.

Each of the ballast plate assembly units 16, 17, 18 and 19 comprises two or more plates and these plates in the water ballast position, as shown in full lines in Fig. 1, are disposed with certain elements thereof lying in the fore and aft direction and certain elements thereof lying athwart ship. The mounting and arrangement are such that at least certain of the athwart elements and fore and aft elements may be collapsed and stored parallel to each other and closely adjacent the athwart bulkheads.

Each assembly unit 16, 17, 18 and 19 embodies a fore and aft partition and an athwart partition. For example, the assembly unit 16 comprises an athwart partition 2S, 3S and a fore and aft partition 5S, 6S, 9C. The assembly unit 17 comprises the athwart partition 4S, 5S and the fore and aft partition 7S, 8S, 9D and the assembly unit 18 comprises athwart partition 4P, 5P and the fore and aft partition 7P, 8P, 9B. The assembly unit 19 comprises the athwart partition 2P and 3P and the fore and aft partition 5P, 6P, 9A. The fore and aft partitions are pivotally fastened to the athwart partitions so that they can be collapsed upon each other for storage against the hold frame structure. In the embodiment shown, the athwart and fore and aft partitions of each assembly unit are each divided intermediate their lengths for minimizing weight and facilitating assembly into the water ballast position and into

the storage position. To this end each assembly unit comprises two separately storable parts. For example, the athwart partition of unit 16 is divided into two parts 2S, 3S and the fore and aft partition is divided into three parts, 6S, 5S and 9C with the athwart part 3S and the fore and aft parts 5S and 9C being collapsible against athwart bulkhead N as shown in dot and dash lines, while the athwart element 2S and the fore and aft element 6S are collapsible upon each other for storage against the center line bulkhead 20B as shown in the dot and dash line. To effect this purpose the part of the assembly unit 16 comprising the athwart element 3S and the fore and aft elements 5S and 9C are movably mounted and fastened to the ship structure for movement from the storage position against the athwart bulkhead N to the full line water ballast position, and in the particular embodiment shown this movable mounting and fastening is by pivotally attaching one end of the partition element 5S, 9C to the athwart bulkhead N, as indicated diagrammatically by the hinge 26 whereby the plate element 5S is moved about the axis of the hinge 26 to and from the storage position and the water ballast position. The athwart plate element 3S and the fore and aft plate element 9C are pivotally fastened to each other about a pivotal axis 27 and these two plate elements are movably mounted to the storage position indicated in dot and dash line, these elements being fastened to the ship structure by the pivotal fastening of the plate 9C to the end of the plate element 5S by means of a pivotal or hinge connection 28.

In the position for water ballast functioning the plate elements 9C and 3S are rigidly fastened at right angles to each other by means of one or more link fastening means 30 but the fastening link 30 is readily detachable at one end so as to permit the swinging of the plate 9C into alignment with the athwart plate 3S in the storage position. The other part of the assembly unit 16 comprising the athwart plate element 2S and the fore and aft plate element 6S are pivotally fastened to each other on the vertical axis 31 and in the particular embodiment shown the athwart plate element 2S is movably mounted and fastened to the ship structure by being pivotally fastened on the vertical axis at 32 to the center line bulkhead 20B and these plate elements 2S and 6S are movable to and collapsible in a position closely adjacent the center line bulkhead 20B.

The assembly unit 17 is similar to the assembly unit 16 and is movably mounted and permanently fastened to the ship structure similarly to the unit 16. In this case the athwart element 5S and the fore and aft elements 8S and 9B are collapsible against the athwart bulkhead O similarly to the elements 3S, 5S and 9C of the unit 16 and the elements 4S and 1S, mounted and fastened similarly to the elements 2S and 6S for movement to and from a storage position against the center line bulkhead 20A. The description of the assembly unit 16 also applies to the assembly units 18 and 19 with the athwart section 5P and fore and aft sections 8P and 9B being collapsible against the athwart bulkhead O and similarly with respect to the athwart section 3P and fore and aft elements 5P and 9A upon the athwart bulkhead N. The elements 4P and 1P are collapsible against the port side of the center line bulkhead 20A and similarly the elements 2P and 3P are collapsible against the port side of the

center line bulkhead 20B. After the assembly units 18 and 19 are moved over to and collapsed into storage positions the hinged or pivotally mounted elements 1 and 1A of the assembly unit 5 20 are swung around into storage position respectively parallel to the center line bulkheads 20B and 20A with parts of the collapsed units 18 and 19 disposed between the elements 1 and 1A and the center line bulkheads. 10 The assembly units 16, 17, 18 and 19 and the movable elements 1 and 1A of the center line assembly unit may be securely fastened in the water ballast functioning position by any suitable means and I have illustrated somewhat diagrammatically such fastening means. The plate elements 1 and 1A are detachably fastened by a means 35. The plate elements 6S and 6P are fastened to the plate elements 7S and 7P by means 36. These plate elements are also provided with a bracing transverse fastening and holding means 38 which at the outer ends 38' are fastened to the side frames of the hold MS and MP, respectively. These transverse bracing and fastening means 38 are fastened to the junction between the plate elements 6S and 7S, the plate 20 6P and 7P and the plates 1 and 1A and as diagrammatically shown in Fig. 1 the fastening of the means 38 are at the fastening means 35 and 36. The fastening means 38 may comprise rods 25 or cables with turn buckles disposed at 36 and other desirable points in the fastening means. The outer ends of the plate elements 3S, 5S, 3P and 5P are secured to the side frames MS and MP by a means 39. When the assembly units 30 35 16, 17, 18 and 19 are not formed in single units as, for example, when they are formed of the separate parts shown and described, these separate parts are firmly fastened together by a fastening means 40 carried by the plate elements 40 6S, 7S and 6P, 7P which fastening means 40 are rigidly fastened respectively to the plates 9A, 9B, 9C and 9D. Thus with five assembly units of collapsible plates a rigid water ballast structure 45 may be readily formed comprising six water compartments on each side of the center fore and aft line of the hold with each half of six compartments functioning independently of the other half except for the spilling of water through openings which may be provided if desired in the center line assembly unit 20, while the movable collapsible plate elements may readily be moved to the storing positions above described and stored in collapsed units against the athwart bulkheads as above described, and in the particular embodiment shown with parts thereof 55 stored against the center line bulkheads. When thus collapsed and stored with the compact units against the bulkheads the hatch is entirely free of the ballast structure so that cargo being loaded 60 is neither damaged itself nor does it injure the ballast plate structure, and the entire hold is free for accommodating cargo except for the very small percentage of the space occupied by the compact collapsed plates stored against the bulkheads. Any suitable means may be provided for holding the collapsed plates in the stored position.

As above described the assembly units 16, 17, 18 and 19 may be movably fastened to and movably mounted with respect to the bulkheads in any suitable manner. In the particular embodiments shown each of these units 16, 17, 18 and 19 comprises two separately movable parts with one part being permanently fastened as by the pivotal connections 26 with the athwart bulkheads and

the other part permanently pivotally fastened to the center line bulkheads. Due to the large weight of these assembly units they are supported by rollers so as to facilitate movement of the units to and from the stored positions and to and from the water ballast functioning positions. The roller support means may be of any suitable character and in the particular embodiment shown (Figs. 3 and 4) this roller support means comprises a plurality of castor roller supports fastened to the plate elements of the assembly units with the rollers engaging and rolling along the inner bottom as a supporting track or floor. In the embodiment shown the plate elements 5P and 5S are supported by the castor roller elements 41 and likewise the plate elements 3P and 3S; the plate elements 6P and 6S by the roller elements 42 and 43, and likewise the plate elements 1P and 1S; and the plate elements 3P, 3S, 5P and 5S by the roller elements 44 and 45.

For further supporting and facilitating the movably and pivotally mounted plate elements and facilitating their movement I have devised a special mount bearing or socket structure shown in Fig. 5. Such pivoted plates are provided with a pivoted shaft 46 whose lower end projects down into a pivot socket structure 47; the socket of the latter is provided at the bottom with a spherical bearing surface 48 and the shaft 46 is provided with a corresponding end surface 46'. The lower end of the shaft is made of slightly less diameter than the diameter of the socket as, for example, there being a difference in diameter of $\frac{1}{32}$ of an inch so as to avoid or minimize side surface friction during the pivotal movement of the plate element about the socket.

The socket structure 47 is provided with a downwardly extending passage 43' on one side thereof for the reception of a lubricant supply means supplying lubricant to the socket bottom and side surfaces, the grease or lubricant supply means being diagrammatically shown at 48'. The side clearance, together with the lubrication, not only minimizes surface friction but also prevents deterioration of the bearing surfaces and seizing or freezing as a result of being submerged in or subjected to salt water from time to time. The socket structure 47 forms a part of the supporting structure for the ballast plate element 49. For example, it may be a part of another ballast plate element which supports the plate element and its pivoted shaft 46; or it may be a part of the plate elements 2S, 2P, 4S and 4P in forming the pivotal support 31 for the plate elements 6S, 6P and 7S and 7P and likewise it may be the pivotal supports 27 and 28 of the plate elements for supporting the associated plate elements. It may form the pivotal supports 23 and 24 for the plate elements 1 and 1A and likewise the pivotal supports 26 of the plate elements 5S, 5P, 8S and 8P. This structure is particularly suited for any of the vertically and pivotally mounted ballast plate elements or units. The pivotal shaft 46 may be mounted on the plate element in any suitable manner as, for example, by means of the welded brackets or arms 49' and at 59 I have indicated hinge elements formed on or fastened to the structural element 51 rigidly connected or formed with the pivoted socket structure 47. These hinge elements 50 maintain the plate element in vertical position with a total weight of the plate supported by the shaft 46 and the pivot socket 47.

The plate elements of the assembly units may be of any suitable structure to obtain the desired

rigidity and strength with a minimum of weight. In Figs. 2, 2A and 2B I have illustrated somewhat diagrammatically a reinforcing means for the plate elements 1 and 1A in the form of detachably strong backs 55 disposed at the top and bottom of the plate elements 1 and 1A. These strong back reinforcing elements 55 are in the form of I beams bridging the hatch stanchions 21, 22 with the lower beam 55 resting upon the ceiling and the upper beam 55 resting at its ends on angle plates 57 welded to the web of the stanchions 21 and 22. These reinforcing strong back members may be fastened to the plate elements 1 and 1A in any suitable manner as, for example, by the means diagrammatically shown at 58 and these members 55 as indicated are thus detachably connected with the plates 1 and 1A and are also detachably connected with the hatch stanchions 21 and 22 as described.

20 The embodiment of Figs. 6 and 7 also includes five assembly units of collapsible and movably mounted ballast plate elements, namely units 16', 17', 18', 19' and 20'. For convenience in illustration the assembly units 16' and 17' are omitted since they are duplicates of 19' and 18', respectively. In this embodiment, as with the embodiment described above, the assembly units 16', 17', 18', 19' are divided into two separable parts when in the stowed position. The assembly unit 19' comprises the ballast plate elements 65, 66, 67 and 68. The unit 18' comprises the plate 65', 66', 67' and 68'. The unit 19' in the particular embodiment shown is separable into the sub-assemblies 65, 66 and 67, 68 and likewise the assembly unit 18' is divided into two separable sub-assemblies 65', 66' and 67', 68'. The sub-assemblies 65, 66 and 65', 66' are collapsible for storage respectively against the athwart bulkheads N and O. The sub-assemblies 67, 68 and 67', 68' are collapsible upon each other and movable to stored position against the fore and aft center bulkheads 20B and 20A. The stored positions of these plates are shown in dot-dash lines.

45 The assembly units 16', 17', 18' and 19' are, like the above modification described, movably fastened to the bulkheads at spaced points. For example, the assembly unit 19' is movably fastened to the athwart bulkhead N at 69 and to the center line bulkhead 20B at 70 and the assembly unit 18' is similarly fastened at the spaced points 69' and 70'. In the particular embodiment shown these fastenings are pivotal fastenings about vertical axes. In the ballast functioning position the plate elements 66 and 67 form in effect a ballasting partition from the center line bulkhead 20B to the side frame MP of the ship and likewise the elements 66' and 67' of the assembly unit 18' form another partition from the center line bulkhead 20A to the side frame MP of the ship. As described however these partitions are conveniently formed in two parts for storage with the fore and aft plates 65, 68 and 65', 68', with these fore and aft plates being collapsed against the athwart plates and stowed against the bulkheads.

50 The assembly unit 20' includes the fore and aft center bulkheads 20A and 20B disposed between the hatch stanchions 21 and 22 and the athwart bulkheads O and N, similar to the center line bulkheads of the above described modification. The other part of the assembly unit 20' comprises two or more collapsible ballast plates which in the assembled position for ballast functioning close the gap between the hatch

55

stanchions 21 and 22 to divide the hold into two separate parts of six compartments each. These fore and aft plates are collectively designated by the numeral 71. In the particular embodiment shown there are three of the plates making up the fore and aft plate 71, namely 71A, 71B and 71C. Also in this embodiment the individual plates 71A, 71B and 71C are in the stowed position collapsed against the ceiling, namely they are pivotally fastened to the ceiling or tank top by means of pivotal or hinged connections 72 so as to be movable from one position to the other about horizontal axes extending fore and aft. The stowed position is shown in the dot-and-dash line in Fig. 6. These plates 71A, 71B and 71C may be constructed in any manner so as to have the desired strength and rigidity with a minimum of weight and they may be reinforced also by a pair of I-beams 55 similar to those described above in Figs. 2, 2A and 2B and fastened to the hatch stanchions 21 and 22 as described above. It is understood that these stowable plates are fastened to the reinforcing beams 55 in any suitable manner and in a detachable manner so that the latter can be stowed away in between deck if desired. The stowable plates may be lifted into position by power means and for hooking the doors to the power means there are provided lifting rings 74. As shown in Fig. 8 the plates 71A, 71B and 71C are locked to the upper I-beam 55 by means of locking pads 75 welded to the I-beams and passing through slots in the plates, and these locking pads 75 are locked in place by the locking keys or wedges 76. The lower I-beam 55 is provided with bridle pads 77 at a point about midway the length thereof for attachment to turn buckles 78 and bridle chains 79. This bridle chain is fastened at 80 to the plate element 68' and another bridle chain 79' leads from a ring bolt 81 to a turn buckle 78' which in turn is fastened by means of a ring bolt 81' to the side frame MP of the ship. The beam 55 may be lifted and carried by power means in engagement with suitable ring bolts.

The sub-assembly units 65 and 66 are rigidly fastened to the sub-assembly units 67 and 68 by a pin fastening means shown diagrammatically at 85 and a similar detachable fastening means is illustrated for fastening the sub-assemblies of assembly unit 18', these fastening means being shown diagrammatically for convenience in exposition. The plate elements 66 and 66' are connected with the side frame MP of the ship in any suitably detachable manner as, for example, by the hinged pin connections 86 which are also diagrammatically illustrated. The plate elements 68 and 68' are also connected together in any suitable manner as, for example, by a similarly detachable hinged and pin connection 86. By the disconnection of the detachable fastening means 85, 86 and by disconnection of the bridle chains 79 and 79' the assembly ballast plate units 18' and 19' may be moved over to the storage positions above described against the bulkheads and there fastened in any suitable manner against movement. Roller supports for the plate elements 66, 68 and 66', 68' are diagrammatically indicated at 88, these being similar to the roller supports 42, 43, 44 and 45 described above.

The ceiling may be mounted on the plates 71A, 71B and 71C in their stowed position and to facilitate the portability of the ceiling it may be made into a multiple number of sections as, for

example, four sections suitably secured together.

In the embodiment of Figs. 1 to 4, the plate elements 2S and 6S and the plate elements 4S and 8S are pivotally fastened at 32 to the center line bulkheads 20B and 20A respectively and at points closely adjacent the I-beam stanchions 21 and 22. The plates 2P and 6P and the plates 4P and 7P are respectively pivotally fastened to the inner sides of the flanges of the I-beams 21 and 22 respectively, while the plates 1 and 1A are pivotally supported at 23 and 24 to the outer surfaces of these flanges. In the embodiment of Figs. 6, 7 and 8 the corresponding plate elements are pivotally fastened directly to the hatch stanchions 21 and 22 and to the outside surfaces of the flanges thereof.

I claim:

1. In a ship cargo hold, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions.

2. In a ship cargo hold defined by athwart bulkheads and side frames, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, at least parts of said athwart partitions being stowable against the athwart bulkheads.

3. In a ship cargo hold, a water ballast structure comprising five assembly ballast plate units dividing the hold into starboard and port sections on the opposite sides of the fore and aft center line of the hold, one of said assembly units

comprising fore and aft center line partitions disposed on the opposite sides of the hatch and a pair of ballast plates pivotally fastened adjacent the inner ends of said center line partitions and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions.

4. In a ship cargo hold defined by athwart bulkheads and side frames, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and a pair of ballast plates pivotally fastened adjacent the inner ends of said center line partitions and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, at least parts of said athwart partitions being stowable against the athwart bulkheads.

5. In a ship cargo hold, a water ballast structure comprising a multiplicity of assembly ballast plate units dividing the hold into starboard and port sections of multiple ballast compartments on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, certain of the other assembly units each comprising athwart partitions extending from points in the vicinity of the inner ends of the center line partitions to the side frames, and fore and aft ballast plates pivotally fastened to said athwart partitions at points intermediate their lengths, said assembly units when in the ballast functioning positions dividing each section of the hold into multiple water ballast compartments, said other assembly units being fastened to the hold structure but movably mounted with respect thereto for ready movement either to stowed and collapsed posi-

tions against the ship hold structure or from the stowed positions to the ballast functioning positions.

6. In a ship cargo hold, a water ballast structure comprising a multiplicity of assembly ballast plate units dividing the hold into starboard and port sections of multiple ballast compartments on the opposite sides of the fore and aft center line of the hold, one of said assembly units comprising one or more fore and aft center line partitions and one or more plates pivotally mounted and movable either to positions forming a continuation of said center line partitions or to positions against the hold structure, certain of the other assembly units each comprising athwart partitions extending from the fore and aft center line to the side frames and fore and aft ballast plates pivotally mounted for movements relative to said athwart partitions, said assembly units when in ballast functioning positions dividing each section of the hold into a multiplicity of ballast compartments, said other assembly units being fastened to the hold structure but movably mounted with respect thereto for ready movement either to stowed and collapsed positions against the ship hold structure or from the stowed positions to the ballast functioning positions, and means fastening said units in ballast functioning positions.

7. In a ship cargo hold, a water ballast structure comprising a multiplicity of assembly ballast plate units dividing the hold into starboard and port sections of multiple ballast compartments on the opposite sides of the fore and aft center line of the hold, one of said assembly units comprising fore and aft center line partitions disposed on the opposite sides of the hatch and a pair of plates pivotally fastened at points in the vicinity of the inner ends of the partitions and movable either to positions closing the gap between the inner ends of said partitions or to positions against the hold structure, certain of the other assembly units each comprising athwart partitions extending from points in the vicinity of the inner ends of the center line partitions to the side frames, and fore and aft ballast plates pivotally fastened to said athwart partitions at points intermediate their lengths, said assembly units when in the ballast functioning positions dividing each section of the hold into multiple water ballast compartments, said other assembly units being fastened to the hold structure but movably mounted with respect thereto for ready movement either to stowed and collapsed positions against the ship hold structure or from the stowed positions to the ballast functioning positions.

8. In a ship cargo hold defined by athwart bulkheads and side frames, a water ballast structure comprising a multiplicity of assembly ballast plate units dividing the hold into starboard and port sections of multiple ballast compartments on the opposite sides of the fore and aft center line of the hold, one of said assembly units comprising fore and aft center line partitions disposed on the opposite sides of the hatch and a pair of plates pivotally fastened at points in the vicinity of the inner ends of the partitions and movable either to positions closing the gap between the inner ends of said partitions or to positions against the hold structure, certain of the other assembly units each comprising athwart partitions extending from points in the vicinity of the inner ends of the center line partitions to the side frames, and fore and aft ballast plates pivotally fastened

11

to said athwart partitions at points intermediate their lengths, said assembly units when in the ballast functioning positions dividing each section of the hold into multiple water ballast compartments, said other assembly units being fastened to the hold structure but movably mounted with respect thereto for ready movement either to stowed and collapsed positions against the ship hold structure or from the stowed positions to the ballast functioning positions, at least parts of said athwart partitions being stowable against the athwart bulkheads.

9. In a ship cargo hold, a water ballast structure comprising a multiplicity of assembly ballast plate units dividing the hold into starboard and port sections of multiple ballast compartments on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, certain of the other assembly units each comprising athwart partitions extending from points in the vicinity of the inner ends of the center line partitions to the side frames, and fore and aft ballast plates pivotally fastened to said athwart partitions at points intermediate their lengths, said assembly units when in the ballast functioning positions dividing each section of the hold into multiple water ballast compartments, said other assembly units being fastened to the hold structure but movably mounted with respect thereto for ready movement either to stowed and collapsed positions against the ship hold structure or from the stowed positions to the ballast functioning positions, said fore and aft partitions being fixed and the plates forming a continuation thereof being movable through 180° for stowage against said fixed partitions.

10. In a ship cargo hold, a water ballast structure comprising a multiplicity of assembly ballast plate units dividing the hold into starboard and port sections on the opposite sides of the fore and after center line of the hold, one of said assembly units comprising one or more fore and aft center line fixed partitions and one or more plates pivotally mounted on vertical axes and movable either to positions in substantial alinement with the partitions to form a continuous fore and aft center line partition or swingable to positions against the hold structure, the other assembly units each comprising athwart partitions extending from points in the vicinity of the fore and aft center line to the side frames and fore and aft ballast plates pivotally mounted at points intermediate the lengths of the athwart partitions and movable with respect thereto, said assembly units when in the ballast functioning position dividing each section of the hold into a multiplicity of ballast compartments, said other assembly units being fastened to the hold structure but movably mounted with respect thereto for ready movement either to stowed and collapsed positions against the ship hold structure or from the stowed positions to the ballast functioning positions, the order of mounting the assembly units in ballast functioning positions being, first, the movement of the fore and aft center line movable plates to ballast functioning position, and, second, the movement of the other assembly units in the same section to ballast functioning position, and the order of moving the units from the ballast functioning position for storage being the re-

12

verse of that indicated for moving to the ballast functioning position.

11. In a ship cargo hold, a water ballast structure comprising a multiplicity of assembly ballast plate units dividing the hold into starboard and port sections on the opposite sides of the fore and aft center line of the hold, one of said assembly units comprising fore and aft center line partitions disposed on the opposite sides of the hatch and a pair of plates mounted on vertical axes disposed in the vicinity of the inner ends of the partitions and movable either to positions closing the gap between the inner ends of said partitions for ballast functioning or to positions 180° from said ballast functioning positions to positions parallel with and adjacent to said partitions, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into a multiplicity of ballast compartments, said other assembly units being movably mounted with respect to the hold for ready movement either to stowed and collapsed positions against the ship hold structure or from the stowed positions to the ballast functioning positions.

12. In a ship cargo hold, a water ballast structure comprising a multiplicity of assembly ballast plate units dividing the hold into starboard and port sections on the opposite sides of the fore and aft center line of the hold, one of said assembly units comprising fore and aft center line partitions disposed on the opposite sides of the hatch and a pair of plates mounted on vertical axes disposed in the vicinity of the inner ends of the partitions and movable either to positions closing the gap between the inner ends of said partitions for ballast functioning or to positions 180° from said ballast functioning positions to positions parallel with and adjacent to said partitions, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into a multiplicity of ballast compartments, said other assembly units being movably mounted with respect to the hold for ready movement either to stowed and collapsed positions against the ship hold structure or from the stowed positions to the ballast functioning positions, said fore and aft center line pivotally mounted plates being swingable in one section of said hold, and the order of mounting said units in said section for ballast functioning operation being first the movement of the fore and aft center line plates from their stowed position, and, second, the movement of the other assembly units in that section from their stowed position and the movement of these units being in reverse order upon movement from the ballast functioning positions to the stowage positions.

13. In a ship cargo hold, a water ballast structure comprising a multiplicity of assembly ballast plate units dividing the hold into starboard and port sections of multiple ballast compartments on the opposite sides of the fore and aft center line of the hold, one of said assembly units comprising one or more fore and aft center line partitions

and one or more plates pivotally mounted and movable either to positions forming a continuation of said center line partitions or to positions against the hold structure, certain of the other assembly units each comprising athwart partitions extending from the fore and aft center line to the side frames and fore and aft ballast plates pivotally mounted for movements relative to said athwart partitions, said assembly units when in ballast functioning positions dividing each section of the hold into a multiplicity of ballast compartments, said other assembly units being fastened to the hold structure but movably mounted with respect thereto for ready movement either to stowed and collapsed positions against the ship hold structure or from the stowed position to the ballast functioning positions, and means fastening said units in ballast functioning positions, certain of the pivotally mounted plates comprising a pivotal mounting member having a rounded convex bearing surface and disposed in a socket support having also a convex rounded bearing surface cooperatively functioning with said first named rounded bearing surface.

14. In a ship cargo hold, a water ballast structure comprising a multiplicity of assembly ballast plate units dividing the hold into starboard and port sections on the opposite sides of the fore and aft center line of the hold, one of said assembly units comprising fore and aft center line partitions disposed on the opposite sides of the hatch and a pair of plates mounted on vertical axes disposed in the vicinity of the inner ends of the partitions and movable either to positions closing the gap between the inner ends of said partitions for ballast functioning or to positions 180° from said ballast functioning positions to positions parallel with and adjacent to said partitions, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into a multiplicity of ballast compartments, said other assembly units being movably mounted with respect to the hold for ready movement either to stowed and collapsed positions against the ship hold structure or from the stowed positions to the ballast functioning positions, certain of the pivotally mounted plates comprising a pivotal mounting member having a rounded convex bearing surface and disposed in a socket support having also a convex rounded bearing surface cooperatively functioning with said first named rounded bearing surface.

15. In a ship cargo hold, a water ballast structure comprising a multiplicity of assembly ballast plate units dividing the hold into a multiplicity of water ballast compartments, certain of said units comprising a pair of relatively movable plates, certain of said plates carrying a pivotal support member having a rounded convex bearing surface and a socket support therefor comprising a corresponding rounded convex bearing surface for supporting the plate.

16. In a ship cargo hold, a water ballast structure comprising five assembly ballast plate units dividing the hold into starboard and port sections on the opposite sides of the fore and aft center line of the hold, one of said assembly units comprising fore and aft center line partitions dis-

posed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, the fore and aft center line pivotally mounted plates resting upon the floor in stowed position.

17. In a ship cargo hold, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, the fore and aft center line pivotally mounted plate means comprising two or more plates pivotally mounted on horizontal axes adjacent the floor for stowage upon the floor when the structure is not being used as a water ballast structure.

18. In a ship cargo hold, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold struc-

ture or from the stowed positions to the ballast functioning positions, the other assembly units being formed in separable parts of two or more plates each.

19. In a ship cargo hold, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, the other assembly units being formed in separable parts of two or more plates each, certain units being separable into two separate parts, one part having two movably mounted plates and the other part having three movable plates.

20. In a ship cargo hold, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, the other assembly units being formed in separable parts of two or more plates each, certain of said units being separable into two parts for stowage, each part comprising two plates.

21. In a ship cargo hold, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly

units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, the fore and aft center line plate means being disposed in the stowed position on the floor and a ceiling is positioned thereover.

22. In a ship cargo hold, a water ballast structure comprising five assembly ballast plate units dividing the hold into starboard and port sections on the opposite sides of the fore and aft center line of the hold, one of said assembly units comprising fore and aft center line partitions disposed on the opposite sides of the hatch and one or more plates pivotally mounted and movable either to positions closing the gap between the inner ends of said partitions or to positions against the hold structure, the other assembly units each comprising athwart partitions extending from points in the vicinity of the inner ends of the center line partitions to the side frames and fore and aft ballast plates pivotally fastened to said athwart partitions at points intermediate their lengths, said assembly units when in the ballast functioning positions dividing each section of the hold into six ballast compartments, said other assembly units being fastened to the hold structure but movably mounted with respect thereto for ready movement either to stowed and collapsed positions against the ship hold structure or from the stowed positions to the ballast functioning positions, the fore and aft center line movable plates being reinforced by a beam when in the water ballast functioning position.

23. In a ship cargo hold defined by athwart bulkheads and side frames, a water ballast structure comprising a multiplicity of assembly ballast plate units dividing the hold into starboard and port sections of a multiplicity of water ballast compartments each on the opposite sides of the fore and aft center line of the hold, one of said assembly units comprising one or more fore and aft center line partitions and one or more pivotally mounted plates forming a continuation of said partitions between the athwart bulkheads, said pivotally mounted plates being movable either to positions forming a continuous fore and aft center position or positions against the hold structure, other assembly units each comprising athwart and fore and aft members cooperating with each other to form ballast compartments and being movably mounted either to ballast functioning positions or to stowed positions against the hold structure.

24. In a ship cargo hold defined by athwart bulkheads and side frames, a water ballast structure comprising a multiplicity of assembly ballast plate units dividing the hold into starboard and port sections of a multiplicity of water ballast compartments each on the opposite sides of the fore and aft center line of the hold, one of said assembly units comprising one or more fore and aft center line partitions and one or more pivotally mounted plates forming a continuation of said partitions between the athwart bulkheads,

17

said pivotally mounted plates being movable either to positions forming a continuous fore and aft center position or positions against the hold structure, other assembly units each comprising athwart and fore and aft members cooperating with each other to form ballast compartments and being movably mounted either to ballast functioning positions or to stowed positions against the hold structure, said fore and aft center line partitions comprising a pair of partitions joining respectively the athwart bulkheads at their outer ends and forming a gap at their inner ends and said pivotally mounted plate or plates being mounted for pivotal movement about vertical axes and disposed adjacent the partitions when not in ballast functioning position.

25. In a ship cargo hold defined by athwart bulkheads and side frames, a water ballast structure comprising a multiplicity of assembly ballast plate units dividing the hold into starboard and port sections of a multiplicity of water ballast compartments each on the opposite sides of the fore and aft center line of the hold, one of said assembly units comprising one or more fore and aft center line partitions and one or more pivotally mounted plates forming a continuation of said partitions between the athwart bulkheads, said pivotally mounted plates being movable either to positions forming a continuous fore and

15
